(57) **CLAIM**

The ornamental design for a photocatalyst filter module for refrigerators, as shown and described.

DESCRIPTION

FIG. 1 is a perspective view of a photocatalyst filter module for refrigerators.

FIG. 2 is a front view of the photocatalyst filter module for refrigerators.

FIG. 3 is a rear view of the photocatalyst filter module for refrigerators.

FIG. 4 is a left-side view of the photocatalyst filter module for refrigerators.

FIG. 5 is a right-side view of the photocatalyst filter module for refrigerators.

FIG. 6 is a top view of the photocatalyst filter module for refrigerators.

FIG. 7 is a bottom view of the photocatalyst filter module for refrigerators; and,

FIG. 8 shows a lid coupled to an upper side of the photocatalyst filter module for refrigerators.

The lid shown in broken lines in the drawings is for illustrative purposes only and form no part of the claimed design.
